COMBINED ELECTRIC LAMP SOCKET AND
SWITCH SLEEVE

Reuben B. Lambert, Terryville, Conn.

Application January 9, 1957, Serial No. 44,449

Term of patent 14 years

(Cl. D26—1)

Fig. 1

Fig. 2

Fig. 3

Fig. 4

Fig. 1 is a side view of a combined electric lamp socket and switch sleeve showing my new design with the sleeve in its uppermost position.

Fig. 2 is a top view of the same.

Fig. 3 is a bottom view of the same.

Fig. 4 is a side view of the same, with the switch sleeve in its lowermost position.

The dot-dash line showing in Fig. 1 of a lamp and supporting pipe is for illustrative purposes only.

I claim:

The ornamental design for a combined electric lamp socket and switch sleeve, substantially as shown and described.
